[57] ABSTRACT

In order to block or fill erosion-produced channels in heat exchanger tube sheets, a plastic rod is provided for insertion into a tube in the exchanger adjacent the erosion channel. The rod peripherally carries an explosive so that the latter is placed in contact with the inner wall of the tube when the rod is inserted therein. The rod is oriented within the tube so that the explosive is adjacent the channel. When detonated, the explosive causes the outer wall of the tube adjacent the erosion channel to flow into the channel without significant distortion of the inner wall of the tube.

FIG. 5.

EXPLOSIVE FORGING OF EXTERNAL SURFACES

BACKGROUND OF THE INVENTION

This invention relates to explosive forging and, more specifically, it relates to the forging of heat exchanger tubes by explosive means into erosion channels in heat exchanger tube sheets.

When tube ends are expanded in tube sheets in heat exchangers, a fit mismatch can occur between the tube sheet and tube. This can result in the formation of very small cavities or crevices between the tube and tube sheet. When a fluid flows into such cavities, they can increase in size to a point where they may extend completely through the tube sheet with the result that fluid can leak out of the heat exchanger through the erosion channels thus formed.

Heretofore, further expansion of the tubes within the tube sheets by explosive forming methods such as that which is described in U.S. Pat. No. 3,411,198, issued Nov. 19, 1968 (hereinafter referred to as "said U.S. Pat."), after such erosion channels have been formed, has been found to be inadequate due to the small width and depth of the channels (usually on the order of 0.020 in. - 0.50 in.). That is, such explosive forming methods are unable to force tube metal into these small channels because these methods produce a relatively uniform expansion of the tube and because the tube thickness imposes restrictions on localized expansion of the tube metal. Furthermore, the disassembly of a heat exchanger to remove the affected tubes in order to fill the channels by welding and grinding is extremely expensive. Therefore, there is presently no satisfactory way to solve the problems created by the formation of erosion channels in heat exchangers.

SUMMARY OF THE INVENTION

This invention comprises the placement of explosives in contact with the inner wall of a tube adjacent an erosion channel so that when an explosive is detonated, that portion of the outer wall of the tube which is adjacent to the erosion channel is forged or expanded into the erosion channel.

A primary advantage of this technique is that it provides a substantial cost saving over prior art techniques since it does not require that the heat exchanger be inoperable for a long time. Additionally, the erosion channels are suitably blocked without significant distortion of the inner surface of the affected tube. This means that flow conditions within the tube are essentially unaffected.

DESCRIPTION OF THE DRAWINGS

FIG. 1 is a perspective view of a portion of a tube sheet showing a typical tube extending therethrough together with an erosion channel in the tube sheet alongside the tube.

FIG. 2 is an end-elevational view of the tube and tube sheet of FIG. 1.

FIG. 3 is a perspective view of an insert containing a peripherally located explosive charge.

FIG. 4 is an end-elevational view of the tube and tube sheet of FIG. 1 with the insert of FIG. 3 positioned therein.

FIG. 5 is a perspective view of the tube of FIG. 1 after the explosive charge contained in the insert has been detonated.

DESCRIPTION OF THE PREFERRED EMBODIMENT

In FIG. 1, the numeral 10 designates a tube sheet through which a plurality of tubes such as that designated by the numeral 12 normally extend. Each tube 12 is positioned within an elongated hole 14 within the tube sheet 10 and is usually expanded therein against the walls of the tube sheet which define the hole 14 by mechanical means or by explosive means such as is described in said U.S. patent. Each tube 12 is characterized by a bore 18 extending therethrough and defined by an inner surface or wall 20.

Erosion channels such as the one indicated by numeral 16 may be formed in the tube sheet 10 adjacent to the outer surface 21 of the tube 12. Such channels 16 may extend along the tube 12 in parallel relation with the tube axis or they may be non-linear as shown in FIG. 1 and FIG. 2.

In FIG. 3, there is shown an insert 22 having an outside diameter of substantially the same size and shape as the inside diameter of the tube 12. The length of the insert 22 will depend upon the shape and length of each erosion channel 16. The insert 22 is provided with a peripheral channel 24 which extends longitudinally of the insert. This channel 24 may be wholly or partially filled with an explosive 26 which is hereinafter referred to as a forging explosive. Additionally, the channel 24 may be open as shown in FIG. 3 or it may have a thin covering of the insert material to aid in retaining the explosive in the insert 22. An explosive 28 (which will be referred to hereinafter as a forming explosive) may be carried axially within the insert 22 for expanding a tube into a tube sheet as described in said U.S. patent.

The insert 22 may be made from any material which will not spall and score the inner surface 20 of the tube 12 when the forging explosive 26 is detonated. Preferably, the insert 22 is made from a castable or extrudable material. Useful materials from which the insert 22 may be made include plastics, rubber and wood.

The explosive which is selected as the forging explosive 26 must be one which will produce a shock wave which is strong enough to cause at least localized extrusion of the tube metal at its outer surface, but which is not so strong that it causes spalling of metal from a tube. The strength of a shock wave which is otherwise sufficiently strong to produce the desired extrusion may, of course, be rendered ineffective for this purpose if it has to travel through materials which cannot transmit the shock or which can transmit it but in reduced strength. Therefore, location of the forging explosive 26 relative to the erosion channel 16 is critical.

The forging explosive 26 must be in substantial contact with the inner surface 20 of the tube 12. Substantial contact is effected by (1) actual contact of the forging explosive 26 with the tube inner surface 20, (2) by positioning the forging explosive 26 in the insert 22 so that the shock passes through only a very thin overlying layer of insert material, or (3) by employing explosive which is provided with a surround or wrapping such as in the case of an explosive sold as Primacord if the tube wall thickness is quite thin, i.e., on the order of 0.020 in. or less. If, in the case of (3), the tube wall thickness is on the order of 0.050 in. - 0.060 in. or greater, a contact explosive should be employed, otherwise the shock wave will not be able to produce extrusion of the tube outer surface region.

The explosive employed as the forging explosive 26 may be any well-known explosive which produces the aforementioned extrusion. For example, any of the following explosives may be employed: strips of Dupont data sheet (containing PETN); pressed composition C-4 (containing RDX); cast explosives such as composition B (60 percent — RDX, 40 percent — TNT); and pressed desensitized RDX.

The explosive employed as the forming explosive 28 may be the same as, or different from, the explosive employed as the forging explosive 26. Thus, any of the above explosives or other explosives such as Primacord may be employed as the forming explosive 28.

In order to fill the erosion channel 16, the insert 22 containing the forging explosive 26 is inserted into the tube 12 to a desired depth (FIG. 4). The insert 22 is rotated until the forging explosive 26 is placed opposite the erosion channel 16 or until the forging explosive 26 is positioned so that it intersects the erosion channel preferably at a plurality of points. Thereafter, the forging explosive 26 is detonated in a conventional manner. As previously noted, the insert 22 may also contain forming explosive 28 and, if it does, the forming and forging explosives may be detonated substantially simultaneously although the forging explosive 26 may be detonated slightly later than the forming explosive 28.

The effects of forging by the herein-described method are shown in FIG. 5. As that figure shows, the outer surface 21 of the tube 12 has been extruded to form a protruding rib 30 having a cross-sectional shape substantially the same as that of the erosion channel 16. It will also be noted in FIG. 5 that the inner surface 20 of the tube has not been significantly altered.

This invention has been described by showing the use of a straight explosive-containing channel 24. However, this is not necessary. Instead, the insert channel 24 can be made to follow the contour of the erosion channel 16 to plug it for a desired continuous distance rather than to plug it at spaced locations as when using

a linear insert channel 16. This is accomplished when the orientation and location of the erosion channel is known and clearly defined.

I claim:

5 1. A method of blocking an erosion channel formed in a metal member adjacent the outer surface of a tube extending through said member, said method comprising:

10 providing an insert which has an outside diameter substantially equal to the inside diameter of a tube and which defines a peripheral channel; inserting a forging explosive into said channel so that said explosive is in substantial contact with the inner surface of said tube, said explosive having sufficient strength to cause extrusion of the material forming said tube adjacent said explosive; slidably inserting said insert into said tube; orienting said insert in said tube with respect to said erosion channel so that at least some of said tube material adjacent said explosive will be extruded into said erosion channel; and detonating said explosive.

15 2. The method of claim 1 wherein said channel in said insert is spaced from and parallel to a longitudinal axis of said insert.

20 3. The method of claim 1 wherein said channel in said insert describes an arcuate path.

25 4. The method of claim 1 wherein said insert contains a forming explosive extending along a longitudinal axis thereof and wherein said method further includes the step of:

30 substantially simultaneously detonating said forming explosive and said forging explosive to cause expansion of said tube into contact with said member and extrusion of some of said tube material into said erosion channel.

35 5. The method of claim 4 wherein said forming explosive is the same as said forging explosive.
